UNITED STATES PATENT OFFICE.

WILLIAM FETZER, OF MIDDLETOWN, OHIO.

TRUCK MECHANISM FOR DRILLS.

SPECIFICATION forming part of Letters Patent No. 723,662, dated March 24, 1903.

Application filed December 22, 1902. Serial No. 136,251. (No m

To all whom it may concern:

Be it known that I, WILLIAM FETZER, a citizen of the United States, residing at Middletown, in the county of Butler and State 5 of Ohio, have invented certain new and useful Improvements in Truck Mechanism for Drills; and I do hereby declare the following to be a full, clear, and exact description of the invention, such as will enable others skilled 10 in the art to which it appertains to make and use the same.

This invention consists in a truck mechanism for drills, and has special reference to the connection of low-down press-drills with front 15 truck-wheels in such a manner that they will not be likely to creel or tip out of proper position when the drill is to be turned in either direction.

It consists in a truck connection for drills 20 comprising means extending downwardly from the frame of a drill to a guiding-truck for the drill, said means projecting to a point near the axis of the truck-wheels, and means connecting the parts at said axis capable of 25 a universal movement.

It also consists in certain other novel constructions, combinations, and arrangements of parts, as will be hereinafter fully described and claimed.

30 In the accompanying drawings, Figure 1 is a perspective view of the truck connection for a drill forming the subject-matter of this invention, the drill being not shown. Fig. 2 is a detail sectional view through the truck 35 connection.

The present invention is designed to supply a truck mechanism for a drill, and more especially a low-down press-drill in which the articulating joint between the frame of the 40 drill and the front truck is brought to a point practically at the axis of said truck, while at the same time draft mechanism for drawing the drill can be applied to the connecting means interposed between the frame and the 45 forward truck at different points between said frame and truck.

In embodying the features of the invention in practical form I secure an iron 1 to the front of the frame, preferably at the end of 50 the stub-tongue 2 of a low-down press-drill. This iron is preferably L-shaped, as shown in Fig. 1, and is formed with a rearwardly-

extending attaching portion 3, which may be riveted, bolted, or otherwise secured to the frame or stub-tongue 2. The forward portion 55 of the said iron 1 is in the form of a vertical leg 4, which extends downwardly to a point just above the axle 5 of a front guiding-truck 6. The lower end of this vertical leg 4 preferably carries a ball or spherical enlarged portion 7, which is inclosed in a socket 8 of suitable structure carried by the front axle. This structure preferably consists of a socket-plate 9, formed with a radiated opening 10 of sufficient size to confine the 65 ball 7 in the socket, but to permit the leg 4 to have considerable forward, backward, or lateral movement, as may be required. The opening 10 is also preferably formed with lateral openings 11 upon opposite sides, 70 so that the socket-plate 9 may be slid upon the flat L-iron until the ball 7 is brought into proper position. The ball 7 preferably rests upon a seat-plate 12, which has a seat or bearing formed thereon for receiving the ball 7, 75 while a portion of said plate extends forwardly and is formed with a boxing or recess, as at 13, for receiving the rear end of the tongue 14 of the front truck 6. The seat-plate 12 and the socket-plate 9 are carried by an 80 axle-plate 15, formed with downwardly-extending flanges 16, which embrace the axle of the front truck, the said axle being held between said projections by means of U-shaped bolts or clips 17. The upper ends of these U-shaped bolts project upwardly through apertures in the axle-plate and in the socket-plate, all the parts being held together by applying nuts to the upper threaded ends of the said clips or U-shaped irons 17. The 85 axle-plate 15 and the seat-plate 12 are secured together and to the end of the tongue 14 by bolts, rivets, or the like or in any other suitable manner. The vertical leg 4 of the iron 1 is braced with respect to the frame or 90 the stub-tongue 2 by a brace-rod 18, extending from said leg 4 at a point near its lower end obliquely back to the frame of the tongue 2. The brace 18 may be riveted or bolted to the leg 4 or may be formed integral therewith, if desired.

As shown in Fig. 1 of the drawings, there is a considerable space left upon the leg 4 above the brace rod or member 18, so that the

clevis 19 may be secured to the said leg in any suitable manner for the attachment of the draft means (not shown) to the drill. It will be seen that the clevis 19 can be clamped 5 or otherwise secured to the leg 4 at varying heights upon said leg as may be desired.

In practice the use of the L-iron is found to prevent the creeling or tipping of the front truck when the drill is drawn to one side or 10 the other, as in turning it about. The tendency heretofore in trucks of a similar kind, but where the pivotal connection of the truck with the tongue of the drill has been above the wheels, was to cause the front truck to 15 creel, often lifting one of the wheels above the ground or otherwise twisting it out of position. By the present invention this tendency is obviated, since the weight of the front of the drill is transferred to a point between 20 the wheels of the front truck near the axis of said wheels, and at the same time means is afforded for the attachment of the draft mechanism for the drill at adjustable points with relation to the front truck and with relation 25 to the frame or stub-tongue of the drill.

Having thus fully described my invention, what I claim as new, and desire to secure by Letters Patent, is—

1. A truck connection for drills comprising 30 means attached to the front frame of the drill and extending downwardly to the axle of a truck, a front truck carrying a bearing for the end of said means, and means for holding the parts together, substantially as 35 described.

2. A truck connection for drills comprising an attaching-iron secured to the frame of the drill and extending downwardly therefrom to the axle of a front truck, a front truck for 40 supporting said iron, and a universal connection interposed between the truck and iron, substantially as described.

3. A truck connection for low-down press-drills comprising an L-iron secured to the 45 frame of said drill and extending downwardly therefrom to the center of a front truck, a front truck for receiving and supporting said iron, and a ball-joint interposed between the end of the iron and the axle of said truck, 50 substantially as described.

4. A truck connection for drills comprising an L-iron having a horizontal leg with an at-

taching portion formed thereon adapted to be secured to the frame of the drill, a vertical leg extending downwardly from said horizontal leg and carrying a ball at its lower end, a truck for supporting said ball, and a socket-plate carried by the axle of said truck for receiving the said ball, substantially as described. 55

5. A truck for press-drills comprising an L-iron secured to the frame of a drill, said L-iron having a forward vertical leg extending downwardly from the said frame, means 60 for bracing the said vertical leg with respect to the frame, a truck supporting the vertical leg, and a universal joint interposed between the said iron and front truck, substantially as described.

6. A truck connection for drills comprising 65 an approximately triangular-shaped iron having a ball at its lower end, a truck for supporting said iron, a socket-plate carried on the axle of said truck, means for holding the said ball in said socket, and a clevis mounted upon the said iron for securing draft means to the iron at different heights thereon, substantially as described. 75

7. A truck connection for drills comprising 80 an L-iron secured to the frame of the drill and having a downwardly-extending vertical leg, a front truck for supporting the same, and a clevis adapted to be clamped at different heights upon the said vertical leg for attaching a draft mechanism thereto, substantially as described. 85

8. A truck connection for drills comprising 90 an L-iron secured to the frame of the drill and having one leg extending downwardly to the center of a front truck, a socket upon said front truck for receiving the lower end of said iron, said socket being formed of a socket-plate and a seat-plate, an axle-plate carrying 95 said seat-plate and socket-plate, means for securing said plates together and to the axle of the front truck, and means for securing the tongue of the front truck to said seat-plate and axle-plate, substantially as described.

In testimony whereof I hereunto affix my signature in presence of two witnesses.

WILLIAM FETZER.
